ATTORNEY

UNITED STATES PATENT OFFICE.

GEORGE E. McCACKEN, OF TAFT, CALIFORNIA.

PUMP.

Application filed April 5, 1923. Serial No. 630,076.

In pumping oil from deep wells it is customary to use a plunger pump provided with a ball valve, the said pump being reciprocated in a tubular discharge column. 5 In the type of pump now commonly used sand is permitted to gather in pockets in the outside surface of the plunger, thereby scoring the opposing surfaces of the discharge pipe and plunger, materially reducing their effective lives and adding materially to the cost of equipment by their necessary constant replacement.

It is the object of my invention to provide a plunger pump for the purpose specified 15 that is so constructed as to effectually prevent the gathering of an erosive material between the plunger and the discharge casting in which it works.

It is another object of my invention to 20 provide a device of the character indicated that will be simple in form and construction, economical to manufacture, durable, and highly efficient in its practical application.

In the drawing:-

25 Figure 1 is a longitudinal section through my improved pump.

Figure 2 is a sectional view on line 2—2 of Figure 1.

30 Figure 3 is a view of another embodiment of my invention, partly in section and part broken away.

Referring more particularly to the drawing, I show at 1 the body portion of the plunger having a flange 2 formed thereon and threaded above and below the flange as 35 at 3 and 4 to receive upper and lower sleeves 5 and 6 as shown, the upper sleeve 5 having an inwardly bevelled upper edge 7 as shown.

The portion 1 has a passage 8 formed 40 longitudinally therein as shown, this passage in the present case being made square whereby to engage a wrench and permit of its easy separation from other parts. In the upper part of portion 1 is removably 45 inserted an element 9 having a valve seat 10 formed in its upper and inner edge to receive a ball valve 11. The outer surface of the upper portion of part 1 is threaded to receive cage 12.

50 Cage 12 comprises an annular portion 13 adapted to be threaded into engagement with the threaded upper portion of part 1,

and carries three upwardly extending bars 14—14—14 terminating in a head 15 threaded as at 16 to receive the lower end 55 of a pump rod not shown.

The cage, of course, permits the upward flow of oil and yet prevents the escape of the freely moving ball 11 which closes off the passage 8 while the plunger is ascending. 60

Assuming now that the pump is in full operation, the oil is moved upwardly as indicated by the arrow. In reciprocating sand or other erosive material has no opportunity to lodge between the casing 17 and the 65 plunger and consequently the life of the instrument is greatly prolonged.

In Figure 3 I show another embodiment of the invention in which the sleeve 18 is internally threaded as at 19 and the annular 70 portion 13 of cage 12 is threaded as at 20 so that a satisfactory smooth wearing surface is secured.

It may now readily be seen that I have provided a structure that is not only simple 75 in form and economical to manufacture, but effectually prevents and entirely eliminates the accumulation of erosive material between the plunger and casing.

It is to be understood, of course, that 80 while I have herein shown and described only two embodiments of the invention, changes in form and construction may be made within the scope of the appended claims. 85

I claim:

In a pump of the character described, an element having externally threaded end portions of equal diameter and one threaded end portion of reduced diameter and having 90 a passage formed longitudinally therethrough and a check valve controlling said passage, a cage threaded on to the threaded end portion of reduced diameter, an annular flange concentrically formed on said element between said threaded end portions of equal diameter, and sleeves of substantially the same external diameter as said flange engaging said threaded ends of equal diameter and brought into contact with said flange whereby to cooperate with said flange 95 to form a continuous cylindrical enclosure 100 for said element.

GEORGE E. McCACKEN,
